UNITED STATES PATENT OFFICE.

MARSHALL E. MOREL, OF SHERIDAN, ILLINOIS.

RAILROAD-TIE.

1,033,032.

Specification of Letters Patent. Patented July 16, 1912.

Application filed February 24, 1912. Serial No. 679,588.

To all whom it may concern:

Be it known that I, MARSHALL E. MOREL, a citizen of the United States, residing at Sheridan, in the county of LaSalle, State of Illinois, have invented certain new and useful Improvements in Railroad-Ties; and I do hereby declare the following to be a full, clear, and exact description of the invention, such as will enable others skilled in the art to which it appertains to make and use the same.

This invention has special reference to railroad ties and more especially to an improvement upon my railway tie, Patent Number, 992,681, filed February 11, 1911.

The primary object of the invention is to improve and simplify the manner of connecting the concrete end blocks of the tie upon which the rails are supported, whereby anything dragging from the train will not catch on the said connecting member and thus injury to the tie will be prevented.

Other objects of the invention are to provide novel means for reinforcing the concrete block and also for resiliently supporting the rails upon the blocks and securely holding said rails thereto.

With the above and other objects in view, the invention consists in the combinations and arrangements of parts as will be herein-after more fully described and claimed, and illustrated in the accompanying drawings, in which:

Figure 1 is a top plan view of my improved railroad tie. Fig. 2 is a side elevation thereof. Fig. 3 is a longitudinal sectional view thereof taken on the line 3—3 of Fig. 1. Fig. 4 is a sectional view taken on the line 4—4 of Fig. 2. Fig. 5 is a sectional view taken on the line 5—5 of Fig. 1. Fig. 6 is a sectional view taken on the line 6—6 of Fig. 2. Fig. 7 is a detail perspective view of one of the receiving casings for receiving the blocks to which the rails are secured.

Referring more specifically to the drawings, wherein like reference characters designate corresponding parts throughout the several views, 10 and 11 designate a pair of concrete blocks forming the terminals of the tie, the same being rectangular shaped as shown and connected by a metallic bar 12 which has its central portion bent in oval form at its opposite longitudinal edges or curved inwardly and downwardly as shown so as not to render an obstruction to a projection suspended from the car whereby the

latter will not tend to injure the bar or tie. Each of the blocks 10 and 11 has its upper portions formed centrally with transverse recesses or openings 13 in which frusto pyramidal casings or receptacles of metal 14 are disposed, the same having closed lower ends 15 and open upper ends for receiving cushion blocks 16 of wood therein. These blocks are preferably forced into the casing from either side of the transverse recesses 13 and through the open ends of the casings, said blocks being retained from displacement by means of downwardly inclined spurs 17 projecting inwardly from the opposite sides of the casings. As will be observed, these casings 14 are also embedded in the tie and are retained therein by means of lugs or projections 18 projecting from the bottom and side portions thereof, it being observed that the upper edge of the casings terminate flush with the top of the blocks in each instance while the cushion members or blocks 16 extend above the concrete blocks above referred to and receive the opposite extremities of the bar 12 thereon. The opposite extremities of the bar are left flat and have disposed there beneath, upon opposite sides of the cushion blocks 16, flat plates or sections of wood 19 which have their inner ends beveled for proper contact with the cushion blocks 16 and which are adapted to keep the bar off the concrete blocks or on to the cushions disposed beneath the bar disposed on opposite side of the blocks 16. The flat end portions of the bar 12 are also formed with elongated slots 20 therethrough, said slots being disposed in staggered relation upon opposite sides of the rails 21 for securing the latter to the blocks 16 by means of spikes 22 which project through the slots and are anchored in said cushion blocks 16 as shown.

As each of the blocks 10 and 11 are similarly constructed and provided for supporting the rails 21 thereon, the above and following description will suffice for both. In this connection, it will be observed that the rails 21 are also prevented from spreading by means of shoulders 23 formed in the bar 12 at the outer side of each of the rails and, in order to further brace the rails, inclined brace members 24 are provided, the same having their lower ends formed with enlarged attaching faces 25 which are secured to the flat portions of the bar 12 by fastening bolts or screws 26 as shown, thereby

rendering these braces removable and adjustable for proper contact with the outer side portions of the balls of the rails at their enlarged upper ends 27. The recesses 13 are also provided for the draining of the tie where the casings 14 and the blocks 16 are mounted therein and in order to conveniently handle the blocks 10 and 11, for the placing and replacing of the tie, depressions 28 are formed in opposite sides of the blocks adjacent each end thereof for receiving suitable carrying tongs.

In order to secure the bar 12 to each of the concrete blocks 10 and 11, vertical fastening bolts 29 are provided, the same being disposed vertically through each of the concrete blocks adjacent each end thereof and having their lower headed ends 30 mounted in recesses 31 or grooves in the bottom of the blocks to assist in the application and removal thereof while the upper ends of the bolts extend through the wooden plates or strips 19 and the bar 12 upon opposite sides of the rails and are secured by nuts 32. These bolts 29 therefore form reinforcing means for the concrete blocks and in order to reinforce the latter, for producing a more rigid structure longitudinal reinforcing bars 33 are embedded centrally of the height of the concrete blocks and have their end portions twisted as shown at 34 and provided with apertures through which the fastening bolts 29 are disposed. By reason of forming each of the blocks 10 and 11 with a single transverse recess 13, it is only necessary to provide a single block 16 for each of the concrete blocks for securing the rails thereto whereas in my former patent, I employed two of such blocks in each concrete block which consequently necessitated the placing of the cushioning blocks within the casing before the latter were embedded in the block and thus the renewal of the cushioning blocks could only be accomplished with great expense since it was necessary to mutilate the concrete blocks and thus reconstruct the same if it was desired to again replace the cushioning blocks therein.

By the above construction, the casings may be embedded in the concrete blocks and the cushioning blocks may be secured therein before or after the concrete blocks are molded and also may be removed therefrom for renewing the same when desired. It will also be seen that the rails can be adjusted toward and away from each other by reason of the slots 20 through which the spikes 22 are disposed.

In order to prevent buckling or bending of the bar 12 centrally of its length, on the action of the heavy trains passing over the concrete blocks of the tie or when the latter are disposed in soft soil, a horizontal brace 35 is provided, said brace being dis-

posed adjacent the lower ends of the concrete blocks and having its extremities twisted as shown at 36 and provided with vertical apertures through which the fastening bolts 29 are disposed, thus preventing outward movement of the lower portions of the concrete blocks. The brace 35 is connected centrally with the portion of the bar thereabove, and this connection is accomplished by means of a bolt member 37 disposed through the bar 12 and secured by a nut 38 while the lower end of the bolt 37 is bent at right angles as shown at 39 and extended through the vertical portion of the brace 35 where it is secured by a nut 40, the said brace 35 and the bar 12 coacting to hold the concrete blocks in a rigid alined position and preventing bending of the bar 12 in either direction.

It will thus be seen that I have provided a very simple and improved railroad tie structure, in which the combination of the concrete blocks and metal bar connecting the same, will form a very rigid structure and the provision of the cushioning block as well as the wooden strips or plates, will serve to decrease the jar upon the blocks and thus prevent injury thereto. The parts are also constructed so as to permit the same to be readily renewed and thus a road bed can be kept in proper order at a low cost.

I claim:

1. A railroad tie comprising a pair of cementitious blocks, a metallic casing mounted in each block and having open ends spaced from the sides of the blocks, cushioning members mounted in the casings and projecting above the concrete blocks, cushioning strips upon opposite sides of said cushioning members carried by each block, a bar removably connected to each concrete block and having its extremities engaged on said cushioning members and strips and rail securing means engaged through the bars and embedded in the cushioning members.

2. A railroad tie comprising terminal members spaced apart, tread members mounted in said terminal members extending above the same, cushioning strips of wood mounted on opposite sides of each of said tread members, a bar having an ovally formed central portion and flat end portions raised over said tread members and cushioning members, braces connected to said bars and extending above the same, rails mounted on the bar and contacted by said braces, securing means for the rails engaged in the tread blocks, means detachably connecting the bar at each end to the terminal members and means connected to each of the terminal members at the intermediate portion of the bars to prevent buckling of the latter.

3. A railroad tie comprising terminal members of concrete, a bar connecting said

members having its end portions resiliently supported upon the upper portions of said terminal members, said bars having elongated slots therethrough, rail securing means 5 extending through said slot, said terminal members having grooves in their bottom portions, vertical fastening and reinforcing bolts disposed through the terminal members and having their lower ends embedded 10 in said grooves with their upper ends engaged through the bar, reinforcing bars connecting said securing members, a brace

member at the lower portions of the terminal members and having its end portions connected to certain of said fastening means 15 and a bolt member connected to the central portion of the bar and the brace between the terminal members.

In testimony whereof, I affix my signature, in presence of two witnesses.

MARSHALL E. MOREL.
